UNITED STATES PATENT OFFICE.

RAY K. HIGGINS, OF WATERBURY, CONNECTICUT.

DESIGN FOR A BOX-COVER.

SPECIFICATION forming part of Design No. 35,371, dated December 3, 1901.

Application filed October 17, 1901. Serial No. 79,052. Term of patent 7 years.

To all whom it may concern:

Be it known that I, RAY K. HIGGINS, a citizen of the United States of America, and a resident of Waterbury, in the county of New Haven, in the State of Connecticut, have invented and produced a new and original Design for Box-Covers, of which the following is a specification, reference being had to the accompanying drawings, forming a part thereof.

My cover may be applied to pocket-cases, boxes, brushes, or similar articles.

In the drawings, Figure 1 is a face view of a box-cover showing my new design. Fig. 2 is a central longitudinal sectional view therethrough.

The leading or material feature of my design consists of the representation of a winged dragon supporting a nude female figure upon a background of clouds and celestial bodies, the whole constituting a substantially rectangular and oblong panel, as shown.

In the drawings, A represents the dragon, having outstretched wings *a*, and B represents the nude female figure, shown as in a 25 reclining position and represented upon the back of the dragon A.

The background comprises clouds *c* and celestial bodies, as stars *d* and a crescent moon *e*.

The cover as a whole is of substantially rectangular and oblong form, as shown.

Having described my invention, what I claim, and desire to secure by United States Letters Patent, is—

The design for a box-cover as herein shown and described.

RAY K. HIGGINS.
